UNITED STATES PATENT OFFICE.

GEORGE C. KNAUFF, OF CHICAGO, ILLINOIS.

FOCUSING-SOCKET.

1,126,786.

Specification of Letters Patent.

Patented Feb. 2, 1915.

Application filed August 11, 1914. Serial No. 856,192.

To all whom it may concern:

Be it known that I, GEORGE C. KNAUFF, citizen of the United States, residing at Chicago, in the county of Cook and State of Illinois, have invented certain new and useful improvements in Focusing-Sockets; and I do hereby declare the following to be a full, clear, and exact description of the invention, such as will enable others skilled in the art to which it appertains to make and use the same.

My invention relates to lamp sockets and reflectors and more particularly to means for readily adjusting the lamp with respect to the reflector so as to bring the lamp filament properly into the focus of the reflector, and to means for insuring a good electrical connection between certain relatively movable parts of the reflector and socket combination.

More specific objects of my invention are to provide a simple and easily manipulated construction which will readily enable the portion of the socket supporting the lamp to be moved with respect to the reflector; to provide simple means for increasing the resistance of the relative parts to such a motion, so as to prevent their being accidentally jarred out of their normal position, while still permitting of an intentional shifting from said position; to provide simple and positive means for locking the relatively movable parts in any given position; to provide simple means for imparting a delicately graduated motion to the lamp with respect to the reflector; and to provide simple and positive means for insuring a good electrical connection between certain of the relatively movable parts through which current is carried to the lamp.

The various objects of my invention may be accomplished with substantially equal facility in a number of different ways, such as those shown on the accompanying drawings, in which—

Figure 1 is a fragmentary view of a reflector equipped with a socket embodying my invention. Fig. 2 is a fragmentary end view of the same. Fig. 3 is an enlarged transverse section through the screw supporting and securing the clamp member of Figs. 1 and 2. Fig. 4 is a perspective view of the said clamp member. Figs. 5 and 6 are fragmentary elevations of other embodiments of my invention. Fig. 7 is a perspective view of the clamp member of Fig. 6.

Fig. 8 is an enlarged fragmentary transverse section through Fig. 6 along the line 8—8.

In each of the three embodiments shown in the accompanying drawings, the lamp 1 is housed by a reflector 2 equipped with an opening through which the base of the lamp projects. Secured to the said reflector by any suitable means, such as a flange 3 overlapping the portion of the reflector adjacent to said opening is a cylindrical shell 4 equipped on one side with a slot disposed either diagonally with respect to the periphery of the casing (as shown at 5 in Figs. 1 and 5) or longitudinally of the casing as shown at 6 in Fig. 6. Slidably mounted within the said shell 4 is the metal casing 7 of the main member of the socket, which main member is equipped with means for coupling the lamp 1 to the forward end thereof and also equipped at its rear end with a terminal 8 for a wire 9 forming one terminus of a circuit, the other terminal 10 of which circuit is grounded to the reflector 2. Mounted upon the main member of the socket and projecting through the said slot in the shell is a stem which in the embodiment of Figs. 2 and 6 consists of the shank of a screw 22 threaded into the said main member and presenting a head disposed outwardly of the shell 4. Carried by the said screw and bearing at both ends against the surface of the shell 4 is a clamp member consisting of an arched spring 11, which clamp member is equipped with a perforation 85 through which the said stem of the screw extends and which may be flexed to alter its curvature by loosening or tightening the screw 22. The slot 5 is preferably disposed diagonally of the casing as shown in Fig. 1, 90 so that if the main member of the socket is rotated with respect to the shell (which may readily be done by manually grasping the bulb of the lamp 1 from the forward end of the reflector and rotating the same in either 100 direction) the sides of the said slot will present cam surfaces engaging the stem of the screw so as to coöperate with the said rotation of the main member relatively to the shell 4 to cause the main member and the 105 lamp carried thereby to be moved longitudinally of the shell 4, that is to say along the axis of the reflector.

The screw 22 is normally screwed up to the point where it will give the resilient 110 clamp member 11 a sufficient tension to cause the latter to engage the surface of the

shell 4 with a pressure which will prevent the said main member from jarring out of its normal position, but which will still permit the above mentioned adjustment 5 when the main member is manipulated with sufficient force to overcome the said pressure. It will be obvious that by loosening or tightening the screw 22 this pressure may be varied as desired, thereby also permitting 10 an adjustment which will compensate for variations in the resiliency of the clamp member, such as those caused by a gradual weakening of the said resiliency when the socket is in service. To avoid a 15 loosening of the screw when the socket is in use, I preferably provide the said perforation in the clamp member with a plurality of ears 12 adapted to receive projections 13 on the under side of the head of the screw, the said projections being rounded so that they will ride out of the said recesses or ears when a sufficient pressure is applied to the screw to rotate the latter in either direction. However, the spring 20 means for maintaining the clamp member in engagement with the shell 4 need not be supplied by the clamp member itself. Thus, 25 Fig. 5 shows a main member of the socket as carrying a threaded stem 14 equipped with a main nut 15 and having associated with both thereof a spiral spring 17 which may be adjusted in tension by moving the said nut 15 upon the threaded stem 14. In this case, the nut 15 may be locked in any pre- 30 determined position by an auxiliary nut 16.

While the spring-pressed frictional engagement of the clamp member with the shell may be sufficient to prevent relative displacement of these parts, I preferably 40 provide the said parts with co-operating formations adapted to interlock so as to afford a positive engagement. Thus, in Fig. 1 I have shown the casing 4 as equipped with corrugations 18 adapted to interlock with 45 teeth 19 upon the respective ends of the clamp member. So also, in Fig. 6 I equip the shell 4 with corrugations 20 disposed circumferentially upon the shell 4 and interlocking with teeth 21 upon the clamp member as shown in Fig. 7.

When the socket of my invention is used with a circuit grounded to the reflector and hence likewise grounded to the shell 4, and with a lamp having one terminal connected to the metal casing 7 of the main member of the socket, the pressure of the above described spring means will draw the said shell 4 and casing 5 firmly into engagement with each other along one side thereof, thus insuring a good electrical connection, which connection will be kept clean by the relative movement of the said parts when the lamp is being adjusted as to its focus. Moreover, by using a diagonal slot 60 as in Fig. 1, I enable the user to effect a

more delicate adjustment of the position of the lamp with respect to the reflector, since the diameter of the bulb of the lamp will always be considerably greater than that of the shell 4, so that the extent of adjustment will be much less than that of the digital rotation of the bulb of the lamp. However, I do not wish to be limited to this or other details of the construction as herein disclosed, since it will be evident 75 that the same might be modified in many ways without departing from the spirit of my invention.

I claim as my invention:

1. A focusing socket including in combination with a lamp, a main member carrying said lamp and having a substantially cylindrical outer surface, a substantially cylindrical casing housing a portion of said main member and equipped with a slot, a stem carried by the main member and projecting through the said slot in the casing, a clamp member carried by the said stem and disposed upon the surface of the casing, and spring means associated with said stem and clamp member for continuously pressing the latter against the casing. 80

2. A focusing socket including in combination with a lamp, a main member carrying said lamp and having a substantially cylindrical outer surface, a substantially cylindrical casing housing a portion of said main member and equipped with a slot, a stem carried by the main member and projecting through the said slot in the casing, a clamp member carried by the said stem and disposed upon the surface of the casing, manually adjustable spring means associated with said stem and clamp member and pressing the latter against the casing, and locking means associated with said stem and spring means for locking the latter in positions within its range of adjustment. 95

3. A focusing socket for a lamp, including a main member carrying said lamp and equipped with a metal shell connected to one terminal of the lamp, a metal casing housing a portion of said shell and slideable with respect thereto and connected to one terminal of a circuit, said shell equipped with a slot; a stem carried by the main member and projecting through the said slot in the casing, a clamp member carried by said stem and engaging the surface of the casing, and means associated with said clamp member and said stem for pressing the latter against the casing to simultaneously lock the said casing and main member against relative motion and press the said casing and shell into firm contacting relation with each other. 110

4. A focusing socket for a lamp, including a main member carrying said lamp and equipped with a metal shell connected to one terminal of the lamp, a metal casing 120

- housing a portion of said shell and slidable with respect thereto and connected to one terminal of a circuit, said shell equipped with a slot; a stem carried by the main member and projecting through the said slot in the casing, a clamp member carried by said stem and engaging the surface of the casing, spring means associated with said stem and clamp member and clamping a portion of the casing between said clamp member and a portion of the body member, and means for adjusting the tension of the said spring; the said spring when under light tension permitting of relative motion of the said casing and body member, and when under more severe tension locking the said body member against motion with respect to said casing.
5. A focusing socket including in combination with a lamp, a main member carrying said lamp and having a substantially cylindrical outer surface, a substantially cylindrical casing housing a portion of said main member and equipped with a slot, a stem carried by the main member and projecting through the said slot in the casing, a clamp member carried by the said stem and disposed upon the surface of the casing, and spring means associated with said stem and clamp member for continuously pressing the latter against the casing, the said 10 portion of the casing and body member, and when under more severe tension locking the said body member against motion with respect to said casing.
15. A focusing socket including in combination with a lamp, a main member carrying said lamp and having a substantially cylindrical outer surface, a substantially cylindrical casing housing a portion of said main member and equipped with a slot, a stem carried by the main member and projecting through the said slot in the casing, a clamp member carried by the said stem and disposed upon the surface of the casing, and spring means associated with said stem and clamp member for continuously pressing the latter against the casing, said slot being disposed spirally upon the casing, the sides of said slot presenting cam surfaces coacting with the said stem to move the main member longitudinally of the casing upon a rotary movement of said body member with respect to the casing.
20. A focusing socket including in combination with a lamp, a main member carrying said lamp and having a substantially cylindrical outer surface, a substantially cylindrical casing housing a portion of said main member and equipped with a slot, a stem carried by the main member and projecting through the said slot in the casing, a clamp member carried by the said stem and disposed upon the surface of the casing, and spring means associated with said stem and clamp member for continuously pressing the latter against the casing, the said 25 portion of the casing and body member, and when under more severe tension locking the said body member against motion with respect to said casing.
25. A focusing socket including in combination with a lamp, a main member carrying said lamp and having a substantially cylindrical outer surface, a substantially cylindrical casing housing a portion of said main member and equipped with a slot, a stem carried by the main member and projecting through the said slot in the casing, a clamp member carried by the said stem and disposed upon the surface of the casing, and spring means associated with said stem and clamp member for continuously pressing the latter against the casing, the said 30 portion of the casing and body member, and when under more severe tension locking the said body member against motion with respect to said casing.
30. A focusing socket including in combination with a lamp, a main member carrying said lamp and having a substantially cylindrical outer surface, a substantially cylindrical casing housing a portion of said main member and equipped with a slot, a stem carried by the main member and projecting through the said slot in the casing, a clamp member carried by the said stem and disposed upon the surface of the casing, and spring means associated with said stem and clamp member for continuously pressing the latter against the casing, the said 35 portion of the casing and body member, and when under more severe tension locking the said body member against motion with respect to said casing.
35. A focusing socket including in combination with a lamp, a main member carrying said lamp and having a substantially cylindrical outer surface, a substantially cylindrical casing housing a portion of said main member and equipped with a slot, a stem carried by the main member and projecting through the said slot in the casing, a clamp member carried by the said stem and disposed upon the surface of the casing, and spring means associated with said stem and clamp member for continuously pressing the latter against the casing, the said 40 portion of the casing and body member, and when under more severe tension locking the said body member against motion with respect to said casing.
40. A focusing socket including in combination with a lamp, a main member carrying said lamp and having a substantially cylindrical outer surface, a substantially cylindrical casing housing a portion of said main member and equipped with a slot, a stem carried by the main member and projecting through the said slot in the casing, a clamp member carried by the said stem and disposed upon the surface of the casing, and spring means associated with said stem and clamp member for continuously pressing the latter against the casing, the said 45 portion of the casing and body member, and when under more severe tension locking the said body member against motion with respect to said casing.
45. A focusing socket including in combination with a lamp, a main member carrying said lamp and having a substantially cylindrical outer surface, a substantially cylindrical casing housing a portion of said main member and equipped with a slot, a stem carried by the main member and projecting through the said slot in the casing, a clamp member carried by the said stem and disposed upon the surface of the casing, and spring means associated with said stem and clamp member for continuously pressing the latter against the casing, the said 50 portion of the casing and body member, and when under more severe tension locking the said body member against motion with respect to said casing.
50. A focusing socket including in combination with a lamp, a main member carrying said lamp and having a substantially cylindrical outer surface, a substantially cylindrical casing housing a portion of said main member and equipped with a slot, a stem carried by the main member and projecting through the said slot in the casing, a clamp member carried by the said stem and disposed upon the surface of the casing, and spring means associated with said stem and clamp member for continuously pressing the latter against the casing, the said 55 portion of the casing and body member, and when under more severe tension locking the said body member against motion with respect to said casing.
55. A focusing socket including in combination with a lamp, a main member carrying said lamp and having a substantially cylindrical outer surface, a substantially cylindrical casing housing a portion of said main member and equipped with a slot, a screw carried by the main member and projecting through said slot in the casing; a resilient clamp carried by said screw and engaging the surface of the casing and the head of the screw, and means associated with said clamp and screw for interlocking the same to prevent rotation of the screw with respect to the clamp and main member.
60. A focusing socket including in combination with a lamp, a main member carrying said lamp and having a substantially cylindrical outer surface, a substantially cylindrical casing housing a portion of said main member and equipped with a slot, a screw carried by the main member and projecting through said slot in the casing; a resilient clamp carried by said screw and engaging the surface of the casing and the head of the screw, and means associated with said clamp and screw for interlocking the same to prevent rotation of the screw with respect to the clamp and main member.
65. A focusing socket including in combination with a lamp, a main member carrying said lamp and having a substantially cylindrical outer surface, a substantially cylindrical casing housing a portion of said main member and equipped with a slot, a screw carried by the main member and projecting through said slot in the casing; a resilient clamp carried by said screw and engaging the surface of the casing and the head of the screw, and means associated with said clamp and screw for interlocking the same to prevent rotation of the screw with respect to the clamp and main member.
70. In testimony whereof I have signed my name in presence of two subscribing witnesses.

GEORGE C. KNAUFF.
